UNITED STATES PATENT OFFICE.

WILLIAM C. EDWARDS, JR., OF KANSAS CITY, MISSOURI.

FIREPROOF STRUCTURE.

1,041,048.

Specification of Letters Patent.

Patented Oct. 15, 1912.

Application filed November 29, 1911. Serial No. 863,095.

To all whom it may concern:

Be it known that I, WILLIAM C. EDWARDS, Jr., a citizen of the United States of America, residing at Kansas City, in the county of Jackson and State of Missouri, have invented certain new and useful Improvements in Fireproof Structures; and I do hereby declare that the following is a full, clear, and exact description of the invention, such as will enable others to make and use the same, reference being had to the accompanying drawings, forming a part of this specification.

The principal objects of the invention are: First. Fabricated metallic structures utilizable in the erection of fireproof walls, floors, roofs and similar purposes either independently or as an embodiment of a form and reinforcement for concrete structures. Second. To interjoin the concrete with reinforcing tubular load sustaining parts of the reinforcement. Third. The erection of metallic walls or partitions without the aid of temporary supports. Fourth. To overcome the lateral distention of fabricated metallic plates of tubular formation and increase its resistance to compression.

The invention relates more specifically to an improvement upon the interlocking parts of a sheet metal structural device for which Letters Patent were granted to me on January 2, 1912, No. 1,013,592.

The invention consists in the novel construction and combination of parts such as will be first fully described and then specifically pointed out in the claims.

In the drawings, Figure 1. is a view in perspective of a building in which the walls, roof and floors are of concrete and metal construction the complete structure being broken away longitudinally with a portion of the roof also broken away and the forward portion of the building shown in cross section with the novel features of the invention shown as an embodiment of a reinforcement to the several parts of the structure. Fig. 2. is a detail view in perspective of the concrete wall of the building with the concrete partially removed therefrom to show the tubular reinforcement and the interlocking distance members. Fig. 3. is a view of a portion of the metal plate showing the slits in the portions of the plate which are subsequently bent to form the triangular tubular portions of the plate, and also showing the channel portion of the plate. Fig. 3^a. is a detail isometric view en-

larged of a triangular tube formed from the plate as seen in Fig. 3. with its parts or members expanded. Fig. 4. is an isometric view of the intermediate portion of the body section of reinforcement bent to form dovetail channel shaped studs of reduced proportions to that of the channel plate and an intermediate distance plate, the parts being expanded, the lower part being broken away. Fig. 5. is a detail vertical sectional view taken through one of the channel plates between the triangular tubular portions on the line x—x in Fig. 2. showing one of the novel spoon lips for the external support and inward conduction of the plastic material. Fig. 6. is an enlarged detail view in perspective of non-expanded tubular interlocked sections as employed in the floor construction of the building seen in Fig. 1. showing the spring tubular truss bars. Fig. 7. is a detail view in perspective of a portion of the expanded tubular portion of the reinforcing plate as employed in the monolithic roof construction showing the truss bar. Fig. 8. is a detail view of a portion of the tubular truss bar. Fig. 9. is a view of the reinforcement in a modified form and embodied in a column construction, a portion of the concrete within the column being broken away to show the expanded and perforated parts of the reinforcement. Fig. 10. is a plan view of a portion of a curved concrete wall with apertures showing the application of the invention thereto.

Similar numerals of reference indicate corresponding parts in all of the figures of the drawings.

Referring to the drawings, 15 indicates the exterior side walls, 16 the monolithic roof, 17 the combined metallic floor and ceiling beneath the roof and 19 a monolithic floor of the fireproof structure, one side wall being shown apertured at 18 to show the reinforcement, and the floor 19 also broken away to show the single section of the reinforcement applied thereto, as in the roof 16. The reinforcement or sheathing structure is composed primarily of metallic plates such as sheet metal, each plate being of considerable width and of the requisite length. The sheet of metal plate 20 see Fig. 3 is bent or pressed on the lines of bending 21° and 22° to form a series of longitudinally extended dovetail shaped corrugations forming tubular cells. As seen in Figs. 2 and 3^a, the parts 22, 21 and 22 constituting said cells are pressed from the original plane of the

- flat sheet leaving the portions 23 of the plate between said cells. The distance between the points or lines 21° and 21° being somewhat greater than between the points or lines 22° and 22° of the completed cell shown in Fig. 3^a. Prior to the bending of the plate 20, see Fig. 3, the portions 22, 21 and 22 of the plate are slit, these slits 21* and 22* being made respectively in the said portions 21 and 22, preferably in the manner shown in Fig. 3, in the form of an acute angle, and in vertical series. The bending lines 21° and 22° in Fig. 3, are indicated by the broken vertical lines. The parts 22, 21 and 22 are then expanded leaving the openings 21* and 22* respectively and a series of narrow strips 24 and 25 respectively (see Fig. 3^a) which are in sequence from one end of the cell to the other end.
- Upon the portions 23 of the reinforcing sectional plate are the spoon lips 28. These lips are formed by segregating a portion of the said plate between horizontal slits 29 and 30 which are parallel with each other and at a suitable distance apart leaving a narrow plate 31 which is bent outwardly from the lines of slits 29 at its upper edge in an outwardly curved line and its lower portion forced inwardly within the slit 30 and past the line of the outer surface of said plate as clearly seen in Fig. 5, thus forming not only a stiffening element to the reinforcement but also serving to support an outer layer of the plastic concreting material and thereby thoroughly embedding the parts 23 and cells within the body concrete.
- The tendency of the water in wet concrete to run down on the outer surface of the reinforcement and carry with it the rich cement is effectually obviated by the spoon formation of the lips, such plastic material being reconducted within the allied body sections of reinforcement into the body concrete.
- In the formation of the tubular cell body section of reinforcement as before described, one end of the metallic sheet or plate is bent inwardly at an angle to the plate to form a non-expanded flange 22''. The parts 22'', 23 and 22 constituting an end stud.
- At a point 21° intermediate the length of the plate 20 as seen in Fig. 2 a short portion of the plate is bent at an angle corresponding to a portion 22 of a similar tubular cell and extended outwardly a distance slightly less than the side 22 of a cell to the point or post 22' as a non-expanded single piece of plate, thence bent and extended in the longitudinal plane of the body section to a point or post 33. This outer part of the plate between the posts 22' and 33 are slit and expanded in the same manner as the portion 21 of the tubular cells and to a width slightly less than the portions 23 of plate 20 between adjacent cells as seen in Fig. 4.

From the point 33 which constitutes a corner post the plate is bent at an acute angle in the same degree as the sides 22 of the cells and in a transverse direction to the body section to the post 35 and the parts 70 slit and expanded in a greater degree, form a distance member, the strips 34 being drawn to their full extent. The heretofore described parts of the plate between the post 21° and 22' and including posts 22' and 33 75 and parts between and portions of the distance members indicated by the strips 34, form the dovetail corrugated stud 32 on the body section.

From the corner post 35 the plate is bent 80 in a reverse direction to the outer side portion of the stud 32 and is slit and expanded as the portion of the stud 32 between the corner posts 22' and 33 is slit and expanded, and this expanded portion is extended in 85 the longitudinal direction of and in a plane parallel with the body section just described to the post 36 a distance corresponding to that between posts 22' and 33 of the stud 32. From the stud post 36 a non-expanded 90 portion of the plate is bent inwardly at an acute angle to a corner post 21° of a cell member with which it is united upon the continuous portion of the body section extending as seen in Fig. 2 a corresponding 95 distance and in opposite directions to the stud 32, the parts described of the plate between and including the corner posts 35 and 36 and a portion of the distance members 34 and the non-expanded part from post 36 to post 21° constituting the stud 37 of dovetail 100 formation upon the continuous portion of the body section; the recesses within the studs opening inwardly as respects combined body sections. From the corner post 21° of the non-expanded part of stud 37, a 105 cell is formed upon the remaining length of the plate reversed in respect to the cells upon the first described portion of the plate and a succession of cells formed in like manner, the plate terminating in a portion or stud 23' which is precisely the same as the portion or end stud 22'', 23 and 22 at the other end of the body section, the stud 23' as well as the parts 23 proper between 110 the cells being provided with the spoon lips.

It will now be seen that in order to combine sections of reinforcement constructed in the manner described for the formation of wall structures of reinforcement and for 115 the erection of hollow partitions or walls with the compartments between as seen in Fig. 2, and extended any length desired, that an end stud 22'', 23, 22 of another similarly constructed body section is engaged telescopically with the stud 32 on the first mentioned body section, and the stud 37 engaged telescopically with the end stud 23' which is as seen opposite in position, thus forming compartments whose sides are 120 125 130

composed of the opposite tubular cell body sections and the respective distance members or plates.

These body sections however may be varied in length and the parts of one body section telescopically engaged with another body section with the same adaptability as if all body sections were of the same length, thus affording superior advantages in interlocking the parts of the reinforcement.

In the upper and lower portions respectively of the upper and lower body sections and of the corrugated members 23, the spoon lips 28 may be wholly removed leaving the openings 31* which are partially formed by the slits 29 and 30 before the removal of the part 31 forming said lip 28.

In the construction of a building embodying the invention as a reinforcement, the combined body sections as seen in Fig. 2 are placed upon a suitable foundation and the compartments between the body sections and distance plates filled with concrete, which concrete immediately passes through the expanded openings, in the distance plates or members, uniting with the strips 34, and also through the sides of the tubular cells, completely filling the cells, and with the expanded parts of which cells the concrete unites. Immediately following the introduction of the concrete within the compartment, a coating of cement concrete is applied to the outer surfaces of the body sections of reinforcement, thoroughly covering the same, and being supported by the spoon lips 28 is prevented from sliding off the reinforcement. The coating of cement concrete thoroughly embeds the spoon lips 28, and such as enters through the lips 31 is united with the body concrete.

Upon the completion of the single course of reinforced concrete wall and of the outer covering of plastic concreting material, the latter is thoroughly troweled, furnishing a finished surface and thoroughly filling the pores in the surface with the rich cement worked, by means of the trowel, to the surface. Another course, of the combined body sections of reinforcement described, is then placed in a vertical position upon the completed first course of reinforced concrete wall, and the cement concrete applied in the manner before described of the first mentioned body section, thoroughly embedding the plates and cells.

In the construction of the combined floor and ceiling 17 as seen in Fig. 1, the body section of reinforcement, while similar in form and arrangement to that seen in Fig. 2, is modified as shown in Fig. 6. In the construction of the reinforcement or sheathing shown in Fig. 6, the triangular tubular cells are not slit and expanded, the flat portions 50 and the sides 51 of the tubular cells being imperforate and bent, in a simi-

lar manner to that shown in Fig. 3^a, to form the cells. Likewise the plates 52, the studs 54 and 55, and the distance plate or member 53, are not slit and expanded but are left imperforate, the proportions however of the 70 studs, distance plates and tubular cells being approximately the same as the corresponding parts shown in Fig. 2. The distance plate 53 in Figs. 1 and 6 however being extended at right angles to the planes of the body sections, the outer portions of which distance plate are bent to form the studs 54 and 55 of dovetail formation. In like manner, to the combination of body sections described and shown in Fig. 2, the 80 studs 54 and 55 of one body section are telescopically engaged within the parts 52, or the end studs upon other combined and similarly constructed body sections.

The body sections, as seen in Fig. 6, may 85 be of the same approximate width for the floor structure as in Fig. 2, or of any increased width as occasion demands, as indicated in Fig. 6.

To sustain the combined floor and ceiling 90 structure, as seen in Figs. 1 and 6, I-beams 56, as shown, are extended beneath the body sections transversely and are supported at their ends within the opposing walls in any suitable manner.

Upon the completion of the side walls of the building the concrete is introduced within the end compartments of the combined body sections of a floor and ceiling construction, as seen in Fig. 1, thus binding the 100 body sections to the walls.

It is obvious that the parts 52 of the ceiling shown at 17 in Fig. 1, may be provided with openings or spoon lips, and the under surface covered with plaster.

Upon the tubular cell body sections thus used as a floor and ceiling structure, a wood floor is shown in Fig. 1, laid upon the metallic surfaces of the body sections, the cells affording a space for the insertion of a strip of wood of like form as seen in Fig. 1, to which the flooring may be nailed in an obvious manner.

Combined with the tubular cell body sections as seen in Figs. 1 and 6, and subsequently with the reinforcement in the roof construction as further explained, are the truss bars 60, which are composed of a narrow plate of suitable length and bent between its longitudinal surfaces to form a 115 portion of a tube 61 and outwardly extended spring flanges 62 as seen in detail in Fig. 8; which flanges are inserted within the cells between the parts 51, the flanges 62 bearing with the pressure imparted by the tubular portion of the spring plate upon the inner surfaces of the sides of the cells, and imparting rigidity thereto. Also as clearly seen in Figs. 1 and 6, it is of great value in preventing possible disengagement of the 120 125 130

interlocking stud 52, and the stud member carried by the distance plate telescopically engaged therewith.

In the embodiment of the tubular cell body sections of reinforcement in monolithic concrete construction, such as in the roof construction shown in Fig. 1, the reinforcement is the same as seen in Fig. 2, and described of such reinforcement, with the distance plate 34 removed, leaving the studs 32 and 37 as specifically described on the divided portions of the body section and omitting the spoon lips. It is then obvious that the divided tubular cell body sections, with the cell parts expanded as previously described, may be joined together in alinement by the engagement of the parts or studs 23 and 23' at the ends of such body sections with the studs 32 and 37 respectively of adjacent alined divided portions of single body sections, and a series of such divided body sections thus interlocked cover the space desired.

The tubular cells, of the reinforcement for the roof construction described, are trussed in like manner as described of the truss bars in Fig. 6. In the introduction of the spring truss bars within the tubular cells, the parts 62 of the truss bar are inserted between the parts 22° of the expanded cells, and below the expanded parts of the said cells, and impart a spring pressure upon the inner surfaces of the sides of the cells and not only prevent the breaking down of the cells and disengagement of the interlocking parts, but forms a matrix for a reinforcing bar as further described and as seen in detail in Fig. 7.

In the application of the concrete to the roof sections of the reinforcement as above described, the concrete covering which is laid upon the upper surface of the reinforcement, floods through the expanded sides of the cells completely filling same, the tubular truss bar preventing any escape of the rich material. Upon the hardening of the concrete in the tubular truss bar, a corresponding bar of concrete is formed, which then acts conjointly with the truss bar to stiffen the roof structure. An important adjunct of this type of roof construction is the saving of the weight and expense of plastering material, the steel acting thoroughly as a reinforcement and imparting a finished under surface.

In the employment of the reinforcement as seen in the roof construction to the monolithic floor construction as seen in Fig. 1 the parts of the divided portions of the body sections are slightly modified, in that the plates 23 as in Fig. 2, are slit and expanded in a similar manner to that described of the outer side part of the stud 32 as seen in Fig. 4, the expanded tubular cell parts 65, as seen in the floor 19, being formed precisely the

same as the cells in the roof and as seen in Fig. 2, the bending posts or points 22° however being in the floor reinforcement farther apart. Also in the floor reinforcement the spring tubular truss bar 60 is omitted.

The embodiment of the reinforcement as seen in Fig. 2, is shown in its application to the construction of columns in Fig. 9, the portion of the body section of reinforcement for the roof structure, without the tubular truss bars but provided with the spoon lips as seen in Fig. 2, is bent into the shape of a column and the end studs 70 engaged and interlocked with the studs 71, which parts are equivalent to the end studs 22'', 23, 22 and 23' and studs 32 and 37 in Fig. 2. When two or more portions of a body section are employed with each other, these parts 70 and 71 are telescopically engaged as heretofore described.

The application of the invention, as seen in Fig. 2 and with non-expanded parts as seen in Fig. 6, is shown, applied to metallic structures of circular or analogous forms, and with compartments which form a metallic wall partition, in Fig. 10. The combined body sections described are shown with the distance plate 77 forming, with the studs 78, the sides to the opening 74. A portion of one of the body cell sections, similar to that employed in the roof construction of the building in Fig. 1, is then bent in the shape of a hollow square, the ends of the plate being bent as shown so as to telescopically engage within the cells 79 of the body sections of the reinforcement, this form of interlocking being similar to that shown in the roof and column constructions. The opening 74 in Fig. 10 and the hollow square described show the manner of forming a door opening and chute in silo construction.

It is obvious that the expanded tubular cell sections may be employed to the construction of the reinforcement as in Fig. 10, and the parts provided with spoon lips, when employed with concrete as a reinforcement.

Upon the hardening of the concrete, the reinforcement is effectually anchored therein. The concrete in adjoining compartments of such reinforcement is identical, because it has passed freely through the distance members while in a plastic state.

The tendency for failure in reinforced concrete structures is for the reinforcement to slip in the concrete, which expanding the cells and permitting the body concrete to fill thoroughly obviates. The only other point at which the sections might fail to thoroughly act as a reinforcement is at the point of telescopic engagement of one end stud around the dovetail stud carried by the distance member of an adjacent section. It will likewise be seen that the concrete bars formed within the tubular cells adja-

cent to those interlocking parts, thoroughly anchors the interlocking parts to their proper position, and hence the structure will not fail until the elastic limit of the 5 steel has been reached.

It is obvious that the tubular cell sections of reinforcement described may be employed without the concrete for such uses as walls to structures of various kinds, and 10 the metal exposed to the weather suitably protected by a coating of paint.

The invention is also applicable to the construction of bridges, tanks, chimneys, wharf revetments and various other purposes. 15

Such other modifications may be employed as are within the scope of the appended claims.

Having described my invention what I 20 now claim as new and desire to secure by Letters Patent is.

1. In a fabricated sheet metal reinforcement comprising oppositely positioned, longitudinally extended recessed studs of dovetail formation and a distance member between said studs, the said studs being attached integrally to the outer edges of the distance member and the recesses in said studs opening in opposite directions, the 25 combination therewith of a separate reinforcement consisting of a sheet metal stud of dovetail formation extending telescopically upon and inclosing the outer surfaces of either of the said recessed studs.

35 2. A fabricated stud and sheathing structure or reinforcement composed of a plate of sheet metal having intermediate its ends a distance member or plate between two side members in parallel planes; each of 40 which side members having one or more longitudinally extended dovetail corrugations and the outer and inner ends of said side members terminate in end studs and recessed studs, respectively, of dovetail formation, said recessed studs being integrally connected with the outer portions of the distance member; the said recessed studs being slightly smaller in cross section than the 45 said end studs carried by their respective side members.

50 3. Fabricated sheathing structures or reinforcement composed of combined plates or sections of sheet metal, each of which plates having intermediate its ends a distance plate or member between two side members in parallel planes, each of which side members having one or more longitudinally extended dovetail corrugations and the outer and inner ends of which side members terminate in end and recessed studs, respectively, of dovetail formation, which recessed studs are integrally connected with the outer portions of the distance member;

said recessed studs being slightly smaller in cross-section and telescopically engaged 65 within the end studs of an adjacent section.

4. A fabricated stud and sheathing structure or reinforcement composed of an expanded metal plate having intermediate its ends a distance member between two side 70 members in parallel planes; each of which side members having one or more longitudinally extended dovetail corrugations, and the outer and inner ends of said side members terminating in end studs and recessed studs, 75 respectively, of dovetail corrugated formation, said recessed studs being integrally connected with the outer portions of the distance member; the said recessed studs being slightly smaller in cross section than the 80 end studs carried by their respective side members.

5. Fabricated sheathing structures or reinforcement composed of combined plates or sections of expanded metal, each of which 85 plates, intermediate its ends, having a distance plate between two side members in parallel planes, each of which side members having one or more longitudinally extended dovetail corrugations and the outer and inner 90 ends of which side members terminate in end and recessed studs, respectively, of dovetail formation, which recessed studs are integrally connected with the outer portions of the distance member; said recessed studs 95 being slightly smaller in cross section and telescopically engaged within the end studs of an adjacent section.

6. In a sheathing structure or reinforcement comprising metal plates having longitudinally extended tubular cells, reinforcements consisting of strips of sheet metal forming tubular spring truss bars having side flanges thereon which flanges are inserted within and bear against the inner 100 sides of said cells.

7. In a reinforcement comprising metal plates and tubular cells fabricated thereon, formed of expanded metal, tubular truss bars and spring flanges carried by the truss 110 bars which bear upon the lower inner surfaces of the sides of the expanded parts of the cells.

8. A fabricated metallic structure composed of a length or sheet of metal plate, 115 portions of which plate having a succession of loops of tubular cell formation, triangular in cross section, formed of expanded metal and a tubular truss bar having spring flanges extending within the cell and bearing upon the inner surfaces of the adjacent sides thereof.
